SEWING MACHINE GUIDE

Jacob Widrow, Carbondale, Pa.

Application September 22, 1950, Serial No. 186,245

7 Claims. (Cl. 112—153)

1

This invention relates to the art of sewing machines. More particularly it pertains to devices adapted for combinative function with sewing machines, and in its preferred embodiments, the invention is directed to guide means for facilitating the expedient production of uniform spaced stitching, such as seams, tucks, hems, edging, as well as the diversified adaptation of trimmings to garments, and any similar manipulations applicable to the sewing art.

Despite the wide resort to guides in the sewing art, and the general element of expediency which they afford, certain difficulties and objectionable features manifest themselves in their usage. Thus the guides within the purview of the prior art do not lend themselves to the flexibility desired in connection with power machine operation and mass production. The usual type of guide which is available occurs as a more or less permanent attachment to the sewing machine table and permits a relatively limited element of adjustment, if any.

This is inconsistent with requisites of commercial production, where the power operated machine may be applied to diversified designs and articles which are materially at variance with each other. In order to obviate limitations of this sort, stamping or marking the fabric is frequently resorted to for the purpose of maintaining the desired uniformity of edge, seam, hem, tuck et cetera. Moreover the prevalent types of guides, which are in effect attached jigs, usually necessitate a distinct element of skill in any efforts to adjust them, and thus the machine operator may be ordinarily incapable of assuming the attendant responsibility for altering the guide pursuant to the given requirements pertaining to varied articles of manufacture within the sewing art.

It is an object of this invention to obviate such difficulties and uncertainties as hereinabove indicated.

Another object is to provide a sewing machine combination including a guide means which lends itself to expedient combinative attachment and to facilitated adjustment over wide ranges of adaptation.

An additional object is to attain a sewing machine combination including a guide which is adapted for facilitated adjustments in sewing machine operations, and affords maximum

2

range and optimum flexibility with respect to the production of uniform spacings of extensive diversification.

A significant object of the invention is a sewing machine guide of simple construction, entirely effective in its operation, and adapted for expedient removable attachment to a machine power table and for facilitated adjustment commensurate with the length of the said table.

10 10 A further object is a removable sewing machine guide attachment, adapted for a power machine table, which permits wide and expedient adjustments in its position without any special requisites of skill.

15 15 An important object is a sewing machine guide comprising an expediently adjustable attachment which lends itself to dependable uniformity in requisite stitch spacings, and which affords a wide variation in its effective uniform adaptations, from an extremely narrow spacing to an unusually wide spacing.

20 20 Other objects, advantages, and features of the invention will become apparent from the following description read in connection with the accompanying drawings in which similar elements are designated by like numerals:

25 25 Fig. 1 is a plan view of the work table and bed of a power sewing machine, with the guide attached thereto, the machine superstructure being omitted and the base thereof shown in cross section.

30 30 Fig. 2 comprises a vertical end view of the work table with the guide attached thereto.

35 35 Fig. 3 pertains to a modified form of guide within the purview of the invention.

40 40 Fig. 4 deals with a detail of a desirable modification of end clamp for attaching the guide to the power work table.

45 45 Fig. 5 comprises another modification, shown as a detail view, of clamp means for affixing the sewing machine guide to the work table.

50 50 Fig. 6 diagrammatically indicates, as an enlarged plan view, a correlation of the guide with the presser foot, pursuant to one adjustment of the invention.

Fig. 7 is directed to another adjustment modification, in similar diagrammatic plan view, showing the coordination of the presser foot with the guide in a manner to afford a particularly restricted stitch spacing of the fabric.

Fig. 8 relates to a third diagrammatic plan view of a modified adjustment in the relative position of the guide with respect to the presser foot.

Referring more particularly to the features of invention embodied in the modifications shown by the various figures of the drawing, it comprises the work table, also referred to as the sewing machine table or machine power table, upon which the sewing machine is mounted. The machine is shown merely by a sectional view of the base 2 of the superstructure, and is mounted on the sewing machine bed-plate 3. Pursuant to the usual type of sewing machines, the said bed-plate 3 is coordinated with a presser foot 4 diagrammatically indicated. It should be noted that the said presser foot is attached, in accordance with normal practice, to the standard of the machine superstructure not shown, and is adapted for functioning in a coordinated position relative to bed-plate 3, pursuant to the prior art. The guide 5 extends transversely of the work table and is shown in one coordinated position relative to the presser foot 4. As indicated, guide 5 is attached to the respective sides 7 and 7' of the work table.

The embodiment of the guide shown in Fig. 1 is provided with a rabbet 6, substantially centrally positioned relative to the longitudinal dimension of the guide. It will be noted that one edge 8 of said guide 5 is entirely uniform, that is, free from any rabbet or slot, such as rabbet 6 shown on edge 9 of the guide.

The position of the rabbet 6 may be subject to variation, as indicated in the guide modification of Fig. 3. Thus guide 10 is fundamentally similar to guide 5 in all respects, except that the rabbet 11 is positioned off center, on one edge or side 12 thereof. The edge or side 13 of this guide modification is uniform, similar to edge or side 8 of guide 5.

It will moreover be understood that the guide may be subject to substantial variation within the scope of the invention. Illustratively rabbets may be provided on both sides of the guide, such as on sides 8 and 9 in the modification of Figs. 1 and 2, or on sides 12 and 13 in the embodiment of Fig. 3. Furthermore more than one rabbet may occur on a given side of the guide, which may be desirable, for example, where machines are positioned in parallel along a given power machine table. In addition the dimensions of the rabbet may be varied in magnitude, dependent upon pertinent requisites of operation and presser foot dimension, and where a guide is provided with more than one rabbet, such as a plurality of rabbets, these may vary relative to each other both as to dimension and configuration pursuant to requirements.

The positioning of a given rabbet of a guide is in effect determinable from the characteristics of the sewing machine structure, and particularly the relationship between the sewing machine and the work table. Thus the rabbet should be located along a guide edge or side in a manner and at a position which will permit it to conform with the presser foot when conformance is desired. In this connection, where substantially wide work or power machine tables comprise a part of the sewing machine, the operative portions of the machine may be positioned off center, and under such circumstances, the rabbet or rabbets of the guide would desirably be off center in order to permit positioning adjacent to and coordinated with the presser foot, as indicated above.

An expedient clamping means as an integral part of the guide is shown in Fig. 4 and comprises a substantially U-shaped spring clip member 15, adapted to fit over the downwardly extending end portion 16 of the guide. Thus the said spring clip 15 comprises an upwardly directed side 17 which is substantially at right angles to the base portion 18. On the other hand, the said portion 19 of the clip is sprung outwardly somewhat, in order to attain the requisite spring actuated contact with side 7 of the power table.

The base 18 of the clip is seated over the end 23 of the guide, and desirably portion 19 of the clip member is provided, in any expedient manner, with a roughened surface 21, adapted to facilitate a gripping effect between the clip member and the power table. A threaded stem 23 of thumb bolt 22 extends through an opening 24 of the side portion 17 of the clip member, and is threaded into a coordinated opening 25 in end portion 16 of the guide, thereby retaining clip member 15 in fitted coordination with the said portion 16 of the guide.

The threading of stem 23 through opening 25 results in the end 26 of the stem projecting therethrough into contact with side portion 19 of the spring clip, and in effect forcing the latter into a releasable tension or pressing contact relative to the said end 7 of the power table, and a clip member 15 is similarly applicable to end or side 7' of the power table. Accordingly through the threaded coordination of the spring clip 15 with end 16 of the guide, the side portion 19, which is forced into contact with the power table, serves to retain the guide in a predetermined position, subject to expedient repositioning or adjustment of the guide as circumstances dictate.

Another quite desirable embodiment of clamping means for attaching the guide to the power table comprises the combination indicated by the detailed showing of Fig. 5. Pursuant to this modification, which is particularly desirable where the guide is fabricated from a synthetic resin or the like, a metal collar 27 may be cast or compressed into the end portion 16 of the guide. Desirably this metal collar includes a flange 28, adapted to snugly fit against the inside of end 16. An inverted U-shaped spring clip member 29 is affixed to the collar flange 28 in any expedient manner, as by riveting or spot welding.

The surface of the spring clip 29, intended for contact with the side 7 of the power table, is desirably roughened in any expedient manner similar to surface 21 on portion 19 of the spring clip 15. In view of spring clips being utilized at both ends of a guide member, a spring clip 29 will likewise apply to end or side 7' of the power table.

A thumb bolt 22, having a threaded stem 23, similar to that utilized in the modification of Fig. 4, is adapted for threaded association with the inner threaded surface comprising the opening 30 of metal collar 27. On threading the stem 23 through the collar, as well as through the flange thereof, the end 26 of the stem effects a contact with the surface 31 of portion 32 of the spring clip, and as a result there may be thus afforded a releasable gripping or pressing engagement between the spring clip and the side 7 of the power table. The attachment of the opposing end of the guide to side 7' of the power table will be through a precisely similar means. In this manner the guide member may be rigidly retained in situ, although subject to expedient repositioning as desired.

It will be noted that the retaining action, whether it be through the spring clip modification of Fig. 4 or that of Fig 5, is actually predicated upon the coordinated effect of the two spring clips at the respective ends of the guide, as indicated above. Thus as shown in Fig. 2, for example, a clamping means is affixed to each of the ends 16 and 16' of the guide, and the retaining function and gripping action is in effect afforded by the combined function of both clamping members, relative to sides 7 and 7' of the power table.

The positioning of the guide with respect to the presser foot is largely determinable by the characteristics of the work contemplated, and the diagrammatic indications of Figs. 6, 7, and 8 are illustrative of the practicable flexibility and simplicity of attachment and adjustment attainable pursuant to the present invention.

Concerning the positioning and adjustment details of the invention, it should be noted that either edge 8 or edge 9 of guide 5 may afford the requisite aligning surface relative to the presser foot, except where an extremely narrow spacing in the form of a seam or tuck or the like is desired. Moreover the guide is adapted and intended for transverse positioning across the entire width of the power table. Thus its longitudinal dimension will desirably exceed that of the power table width to an extent sufficient to permit the guide either to lie upon or proximate to the power table, with ends 16, 16', positioned sufficiently close to sides 7 and 7' of the table for attaining the requisite gripping and retaining function by the clamping attachments affixed to said ends.

In accordance with Fig. 6, which is essentially an enlarged detail of the relative position of guide and presser foot shown in Fig. 1, the guide member 5 extends transversely of the power table, as previously stated, and is located at the right of the presser foot 4, with the side 8 of the guide being in substantial proximity to the edge 34 of the presser foot. Pursuant to this modification, the adjustment of the guide relative to the presser foot is restricted substantially to the space between the said presser foot 4 and the base 2 of the machine superstructure. As an illustrative indication, and not limitative, this distance may approximate 7 inches more or less for the average power machine, and it will be understood that this may be subject to variation dependent upon the characteristics of a given machine.

With further reference to Figs. 1 and 6, the dimension of the seam, hem or tuck available by the positioning of the guide as shown comprises approximately the distance between hypothetical line 35 and side 8 of the guide. In this connection the said line 35 in effect corresponds with the needle path or stitching line, and is positioned substantially midway of the presser foot opening 36. Thus the pertinent hem, seam or tuck may be subject to enlargement by locating the guide at any predetermined position transversely of the power table, between the edge 34 of the presser foot and the said base 2 of the machine superstructure.

The sketch indicated by Fig. 7 likewise positions the guide 5 to the right of edge 34 of the presser foot. However the side 9 of the guide is directed toward the said presser foot, and in fact the edge 34 thereof is located essentially within the rabbet 6. With this adjustment of guide 5, it will be seen that an extremely narrow hem, seam or tuck of requisite uniformity is attainable. Referring to the aforesaid hypothetical median line or needle path 35, the dimension of

the hem, tuck or the like in this modification will approximate the distance between the said line 35 and the edge or side 9 of the guide member. It will nevertheless be understood that even though the rabbet is directed toward edge 34 of the presser foot, the guide may be subject to positioning anywhere in the zone 33 between the median line 35 of the presser foot and the base 2 of the machine superstructure.

Fig. 8 reveals the guide positioned to the left of the presser foot, thereby affording comparatively unlimited variation in positioning the guide transversely of the power table, the limitations being determined by the length of that portion 15 of the power table which extends to the left of the presser foot 4. As shown in Fig. 8, side 8 of guide 5 is located in proximity to edge 37 of the presser foot, and the dimension of the hem-seam or tuck, pursuant to this adjustment, comprises the distance between the said median stitching line or needle path 35 and the said edge 8 of the guide. As the guide 5 is adjusted in zone 33 toward the left, the distance between line 35 and edge 8 will be progressively increased, and the pertinent dimension may be extended to the point where the guide 5 is positioned along the edge 38 of the power table.

While the showing of Fig. 8 positions edge 8 of the guide member toward edge 37 of presser foot 4, it will be understood that edge 9 of the guide member likewise may be positioned contiguous edge 37 of the presser foot, and under such circumstances, the rabbet 6 may be correlated with the said presser foot edge 37. By this expedient the advantages attainable from the rabbet, especially that of affording an extremely narrow, uniform hem, tuck or the like, is provided when the guide 5 is located on the left of the presser foot with the said rabbet 6, on edge or face 9 of the guide, adjacent edge 37 of the presser foot.

Accordingly the positioning of the guide to the left of the presser foot permits the forming of very narrow, accurate hems, tucks, seams, or any desired stitched spacing of improved uniformity similar to that afforded by the attachment of the guide to the right of the presser foot, the requisite being that the rabbet 6 shall be contiguous the pertinent presser foot edge. Thus while positioning the guide on the right of the presser foot affords the possibilities for progressive variations in the width of the stitched spacing that are essentially limited to the distance between line 35 and the base 2 of the machine superstructure, exclusive of the surface width 40 of the guide, the progressive width variations attainable through locating the guide on the left of the presser foot are substantially determinable by the distance between line 35 and edge 38 of the power table, likewise exclusive of the surface width 40 of the guide 5.

Accordingly in view of its flexibility in adaptation both to the right of the presser foot and to the left thereof, the guide 5 comprises a simplified, adjustable device permitting accurate, uniformed stitched spacings, which are subject to predetermined and widely diversified dimensions relative to the needle path or stitching line 35. This is evidenced by its sphere of function extending longitudinally of the machine power table substantially from edge 38 thereof to the said superstructure base 2, or differently stated, from said table edge 38 to median line 35 on the left of the presser foot and from said line 35 to

the superstructure base 2 on the right of the presser foot.

The above description has illustratively referred to guide 5 in the consideration of the various adjustments attainable, as exemplified in reference to Figs. 6, 7, and 8. However it will be clear that guide 10 is subject to similar adjustable positioning and affords comparable attributes of flexibility in its adaptations, as well as accuracy and uniformity as a power table guide, since the said guide 10 is to all intents and purposes fundamentally similar to guide 5. As indicated hereinabove, the difference between guide 5 and guide 10 is predicated on the positioning of the rabbet 6, this being essentially determinable by the characteristics of the sewing machine, particularly with respect to the pertinent location of the machine superstructure together with the presser foot location relative to the transverse dimension of the power table. Differently stated the position of the presser foot with reference to the side or edge 7 or 7' of the power table is determinative of the position of the rabbet along the longitudinal dimension of the guide.

As for the dimension of the guide, its length will be determined, as previously indicated, by the transverse dimension of the power table, with the angularly disposed portions 16, 16' thereof being of sufficient length to permit the engagement of the attached clamping means with the sides 7, 7' of the power table. Since the width or transverse dimension of sewing machine tables is essentially standardized, the regulated production of appropriate length guides, pursuant to the invention will be apparent to those versed in the art.

Merely by way of example, the longitudinal dimension of a desirable fabricated guide embodiment applicable for a known sewing machine power table, measured between the inner surface of angularly disposed portions 16, 16', is approximately 16.5 inches. As for the surface width thereof, this dimension may be substantially subject to the dictates of preference, and for the said fabricated guide embodiment, this dimension is approximately $\frac{5}{8}$ inches. As in the case of the other guide dimensions, the height or thickness of the guide may be determinable largely on the basis of preference, and the relevant dimension of the said guide embodiment is approximately $\frac{1}{4}$ inches.

In connection with the angularly disposed portions 16, 16', the effective length thereof may likewise be subject to variation dependent, for example, upon the dimensional characteristics of the power table, and in the aforesaid guide embodiment the length is approximately $1\frac{1}{8}$ inches measured from the under face of the guide—that is, along the inside surface of said portions 16 or 16' and thus excluding the thickness or depth of the longitudinal portion of the guide, which as indicated, is positionable transversely of the tables and may be approximately $\frac{1}{4}$ inch in height or thickness. By way of reiteration, the designated dimensions are merely illustrative of a desirable embodiment and are in no sense critical or in any manner intended to be restrictive of the invention.

The guide member may be fabricated from diversified materials, such as metals, synthetic resins including artificial rubber-type materials, as well as from natural rubber, et cetera. While the clamping means shown in Figs. 4 and 5, preferably of metal derivation, are applicable to any

of the indicated types of guide materials, the modification of Fig. 4 is more expediently adapted for metal guide members than for resin or similar guides, in view of the greater amenability to threading manifested by metal articles. As for the clamping attachment of Fig. 5, this is entirely effective with synthetic resins, rubber-type materials and the like, as well as with metals.

While it is not intended to be restricted to any particular type of material for fabrication of the guide, quite desirable metals have been found to be aluminum as well as various alloys thereof, and steel, et cetera. Similarly effective are resin guides, such as those derived from Lucite, phenol-aldehyde resins, polystyrene resins, etc.

The procedure involved in the utilization of the invention will conform with the fundamentals pertaining to the supply of fabric to the power table of a sewing machine for the purpose of applying predetermined stitched spacing thereto. Thus the fabric is normally fed transversely of the power table—that is, across the same, and a folded end of the fabric, determinative of the width of the stitched spacing may be positioned adjacent the edge 8, or 9, in accordance with the predetermined adjustment of the guide 5, while the line of stitching is determined by the position of the presser foot. As the folded edge of the fabric is passed across the power table in contact with the pertinent edge of the guide, the stitching, conforming with line 35 is provided by the usual function of the needle in coordination with the presser foot.

Whether the guide 5 will be placed to the right 35 of the presser foot or the left thereof, and the relevant positioning of the rabbet 6 with respect to the presser foot will be subject to the nature of the spaced stitching requirements and determinable by the operator versed in the sewing art.

Where the distance between line 35 and base 2 of the machine superstructure is approximately 7 inches, and the spaced stitching desired is less than 7 inches, the guide 5 may effectively be located on the right of the presser foot. This location of the guide is desirable, where it is expedient as above indicated in view of the predetermined width of the spaced stitching, since it permits the length of zone 33' of the power table, extending from the line 35 to edge 32, for the handling of substantial lengths or masses of fabric. Similarly this location of guide 5 is effective for extremely narrow stitched spacings attained through the positioning of rabbet 6 to the right of and contiguous presser foot 4.

Where the spaced stitching desired exceeds that attainable with the positioning of guide 5 to the right of the presser foot, it is essential that the guide be placed to the left thereof. As previously indicated, this location of guide 5 permits the production of spaced stitching from that of an extremely narrow width when rabbet 6 is contiguous edge 31 of the presser foot, to an unusually enlarged width attainable by the adjustment in the location of guide 5 toward the edge 33 of the power table, as aforesaid. As previously indicated the maximum width of stitched spacing with the positioning of guide 5 to the left of presser foot 4 corresponds with the distance between line 35 and the edge or side of the guide 60 which faces the presser foot, the opposing side or edge of the guide being aligned with edge 32 of the work or power table.

Pursuant to the invention, there is provided a comparatively simple, sturdy guide member, especially applicable in a combinative association

with a sewing machine, attachable to the machine power table, and affording a diversified flexibility in its adjustment and function not heretofore attainable. Thus the adjustable and variable positioning of the guide member permits an unusually wide latitude in the forming of stitched spacings of enhanced accuracy and uniformity, from those of extremely narrow width progressively to those of extremely enlarged width. By virtue of its characteristics, the invention is adapted for use by any sewing machine operator and without any unusual requisites of mechanical skill. Moreover indicative of the features and utility of the invention are the many adaptations and flexibility thereof pertinent to the formulation of spaced stitching of improved accuracy and uniformity and subject to extremely wide variations in the relevant dimensions such as the spacing width. As previously described, the ramifications of the said stitched spacings illustratively include the production of hems, tucks, seams, edging, as well as the attachment of diversified types of trimmings to a garment.

In accordance with the disclosure herein, the details of description pertaining to the various figures of the drawing are directed to preferred modifications of the invention. It will, however, be understood that these desirable embodiments are intended to be essentially illustrative, rather than restrictive or limitative, and are subject to substantial variation within the purport and scope of the invention herein.

While I have described my invention in accordance with desirable embodiments, it is obvious that many changes may be made in the details of construction, and in the combination of parts and materials, without departing from the spirit of the invention as defined in the following claims.

Having thus set forth my invention, I claim:

1. In a sewing machine combination, a bed-plate, a machine power table supporting said bed-plate, a presser foot supported for functioning in a position coordinated with and relative to said bed-plate, an elongated guide member extending transversely of said power table and parallel to said presser foot in its said position relative to the bed-plate, the longitudinal dimension of said guide member at least corresponding with the dimension of the power table it overlies, the said guide member having end portions angularly disposed relative thereto, each said end portion being positioned contiguous a respective side of the table, a clamping means integrally coordinated with each said end portion of the guide member, said clamping means being removably and adjustably attached to an opposing side of the power table, whereby the said guide member is adapted for adjustable and variable positioning relative to the presser foot, to the right and to the left thereof.

2. In a sewing machine combination, a bed-plate, a machine power table supporting said bed-plate, a presser foot supported for functioning in a position coordinated with and relative to said bed-plate, an elongated guide member extending transversely of said power table and parallel to the said presser foot in its said position relative to the bed-plate, the longitudinal dimension of said guide member at least corresponding with the dimension of the power table it overlies, the said guide member having at least one rabbet adapted for correlated positioning relative to said presser foot, the said guide

member having end portions angularly disposed relative thereto, each said end portion being positioned contiguous a respective side of the table, a clamping means integrally coordinated with each said end portion of the guide member, each said clamping means being removably and adjustably attached to an opposing side of the power table, whereby said guide member is adapted for adjustable and variable positioning to the presser foot, to the right and to the left thereof.

3. In a sewing machine combination, a bed-plate, a machine power table supporting said bed-plate, a presser foot supported for functioning in a position coordinated with and relative to said bed-plate, an elongated guide member extending transversely of said power table and parallel to the said presser foot in its said position relative to the bed-plate, the longitudinal dimension of said guide member at least corresponding with the dimension of the power table it overlies, the said guide member having end portions angularly disposed relative thereto, each said end portion being positioned contiguous a respective side of the table, a clamping means integrally coordinated with each said end portion of the guide member, said clamping means comprising a U-shaped spring clip member, and means threadedly coordinated with each said end portion, for passage therethrough and through one side of said clamping means, the said threadedly coordinated means releasably pressing one side of said spring clip member into holding contact with the table, whereby said guide member is adapted for adjustable and variable positioning relative to the presser foot, to the right and to the left thereof.

4. A guide means for a sewing machine comprising an elongated member adapted for positioning transversely of a sewing machine table, the longitudinal dimension of said elongated member at least corresponding with the dimension of the table it is adapted to overlie, said guide means having at least one rabbet adapted for correlated positioning relative to a presser foot operatively positionable relative to the sewing machine table, the said guide member having end portions angularly disposed relative thereto, each said end portion being adapted for positioning contiguous a respective side of the table, a clamping means coordinated with each end portion comprising a U-shaped spring clip member, and means threadedly coordinated with each said end portion, for passage therethrough and adapted to releasably press said spring clip member into holding contact with the table.

5. A guide means for a sewing machine comprising an elongated member adapted for positioning transversely of a sewing machine table, the longitudinal dimension of the said elongated member at least corresponding with the dimension of the table it is adapted to overlie, the said guide member having end portions angularly disposed relative thereto, each said end portion being adapted for positioning contiguous a respective side of the table, a clamping means coordinated with each said end portion and comprising a U-shaped spring clip member, and means threadedly coordinated with each said end portion and passage therethrough and through one side of said clamping means, the said threadedly coordinated means being adapted to releasably press one side of said spring clip member into holding contact with the table.

11

6. A guide means for a sewing machine comprising an elongated member adapted for positioning transversely of a sewing machine table, the longitudinal dimension of said elongated member at least corresponding with the dimension of the table it is adapted to overlie, said guide means having at least one rabbet adapted for correlated positioning relative to a presser foot operatively positionable relative to the sewing machine table, the said guide member having end portions angularly disposed relative thereto, each said end portion being adapted for positioning contiguous a respective side of the table, a U-shaped spring clip member fitted over each end portion, and means threadedly coordinated with said end portion for passage therethrough, and through one side of the spring clip member, said means being adapted for releasably pressing the other side of the spring clip member into holding contact with the table.

7. A guide means for a sewing machine comprising an elongated member adapted for positioning transversely of a sewing machine table, the longitudinal dimension of said elongated member at least corresponding with the dimension of the table it is adapted to overlie, said guide means having at least one rabbet adapted for correlated positioning relative to a presser foot operatively positionable relative to the sewing machine table, the said guide member having end portions angularly disposed relative thereto, each said end portion being adapted for

12

positioning contiguous a respective side of the table, a metal collar integral with each of said end portions, an inverted U-shaped spring clip member attached to each metal collar on the inner side of the said end portions, and means threadedly coordinated with each said end portion for passage therethrough and through the said collar, said threadedly coordinated means being adapted for releasably pressing one side of the spring clip member into holding contact with the table.
